APPARATUS FOR STERILIZING LIQUIDS BY MEANS OF ULTRA-VIOLET RAYS.

1,193,143.

Specification of Letters Patent

Patented Aug. 1, 1916.

Original application filed June 7, 1910, Serial No. 565,611. Divided and this application filed February 12, 1914. Serial No. 818,209.

To all whom it may concern:

Be it known that we, VICTOR HENRI, a citizen of the French Republic, residing at Paris, France, ANDRÉ HELBRONNER, a citizen of the French Republic, residing at Suresnes, France, and MAX VON RECKLINGHAUSEN, a subject of the German Emperor, residing at Suresnes, France, have invented a new and useful Improvement in Apparatus for Sterilizing Liquids by Means of Ultra-Violet Rays, of which the following is a specification, this application being a division of application Serial No. 565,611, filed June 7, 1910.

15 This invention relates to the sterilization of liquids and more particularly to the sterilization of those liquids which are only slightly or not at all opaque to ultra-violet rays. Water for example is such a liquid.

20 It has already been proposed to sterilize water by inserting in conduits or channels through which the water flows mercury vapor lamps having containers of quartz or silica. These lamps emit ultra-violet rays 25 and as quartz or silica is transparent to these rays they are able to pass freely into the surrounding water. This method, however, does not utilize the rays to their fullest efficiency owing to the cooling of the lamp by 30 the water which produces a harmful effect on the electrical characteristics of the lamp which will emit fewer rays when water cooled than when operating normally in the atmosphere and only cooled by the movement 35 of the surrounding air.

According to our invention, instead of immersing the lamp or source of ultra-violet rays in the liquid, we place it outside and cause the liquid to flow past the lamp in a 40 zigzag or undulating fashion, this being accomplished by causing the liquid to flow through a trough provided with baffle plates or otherwise so arranged as to cause the liquid to flow in the desired manner.

45 In order to utilize the rays emitted to their fullest possible extent, the lamp or other source is provided with a reflector and the sides of the troughs and baffles are made of a reflecting material, such as polished 50 metal, so that the rays which pass through the liquid are caused to re-traverse the same and are therefore utilized to their fullest extent.

The liquid may be caused to pass and re-pass through the rays in several different ways. Assuming that the lamp is located over the liquid then the liquid may be caused to move up and down or toward and away from the lamp in which case the direction of movement of the liquid will be substantially parallel with the direction of the rays, or the liquid may be caused to move in a zig-zag path in a horizontal plane, in which case the direction of movement is substantially perpendicular to the direction of the rays.

In another method of carrying out the invention, the liquid is caused to traverse a spiral path, the spiral being formed on the surface of a cone and the lamp located within the entrance of the cone. With this arrangement the rays are utilized very efficiently and with a small apparatus.

In the accompanying drawings we have shown in a diagrammatic form various methods by which our invention may be carried out in practice.

Figure 1 is an elevation, partly sectional, of one form of apparatus, Fig. 2 is a plan of another form of apparatus and Figs. 3 and 4 are elevations, partly sectional, illustrating other modified forms of apparatus.

Referring to Fig. 1, the source of ultra-violet rays is indicated as being a mercury vapor lamp 1 having a quartz container and provided with a reflector 2, the liquid to be sterilized is admitted through a pipe 3 to a trough 4 provided with a series of baffle plates 5 arranged with spaces at the top and bottom alternately so that the liquid is caused to pass through the trough in the direction of the arrows to the outlet 6; in order to utilize the effect of the rays to the fullest extent, the sides of the trough and the baffle plates are made of reflecting material.

In Fig. 2 the trough takes the form of a zigzag tube arranged in a horizontal plane provided with an inlet 7 at one end and an outlet 8 at the other end, the flow of liquid taking place in the direction of the arrows.

In Fig. 3 the trough is of a spiral form and is arranged so that the liquid in its passage along the same is exposed at all parts to the influence of the ultra-violet rays.

Fig. 4 shows an apparatus in which the liquid is withdrawn from the influence of

the rays at certain parts of its passage. In this arrangement which is substantially similar to that of Fig. 1, certain of the baffles are united at the top by plates 9 which are 5 impervious to the ultra-violet rays, so that when the liquid is traversing a space below said plates it will be removed from the influence of the rays.

In all the arrangements the interior surfaces of the conduits and baffle plates should 10 be made of reflecting material so that the effect of the ultra-violet rays may be fully utilized by causing them to traverse back and forth through the liquid.

15 It will be observed that, since the liquid is only slightly opaque, even if it is not absolutely transparent to the ultra-violet rays, we are able to use conduits or troughs of considerable depth as the effect of the rays 20 upon the inner layers of the liquid is little diminished by the effect of their passage through the outer layers.

It is desirable to arrange the baffle plates and troughs or conduits in such a manner 25 that the liquid will flow at the same rate through all parts of the apparatus by which means every particle of the liquid is subjected to the influence of the rays for the same period of time, whereby the whole of 30 the liquid is equally sterilized.

We claim as our invention:

1. In apparatus for sterilizing liquids, the combination with a source of ultra-violet rays, of a channel or conduit through which 35 the liquid may flow, said conduit being formed to present a restricted tortuous path

for the liquid closely passing and repassing and directly exposed to the rays from said source, and means for agitating the liquid in its passage through the channel. 40

2. In apparatus for sterilizing liquids, the combination with a source of ultra-violet rays of a channel or conduit through which the liquid may flow, said conduit being located in close proximity to the source and 45 exposed to the direct action of the rays from the same, baffle plates placed in the conduit to form a restricted tortuous path for the liquid closely passing and repassing said source whereby the entire body of liquid will 50 be caused to flow repeatedly in a thin film through the field of such rays.

3. In apparatus for sterilizing liquids, the combination with a single source of ultra-violet rays, of a trough placed in the vicinity 55 of the same and exposed to the direct action of the rays from the source, baffle plates supported in the trough to form a series of compartments and a tortuous path for the entire body of liquid closely passing and re-passing through the field of said rays, a plurality of said compartments being simultaneously illuminated by the rays.

In testimony whereof we have hereunto subscribed our names this tenth day of May 60 1913.

VICTOR HENRI.
ANDRÉ HELBRONNER.
MAX VON RECKLINGHAUSEN.
